STORAGE AND DISPLAY RACK

Robert R. Citron, Stockton, Calif.

Application March 30, 1959, Serial No. 802,719

2 Claims. (Cl. 211—113)

This invention relates to a storage and display rack. More particularly, this invention relates to a divided, shelf-like cover for the lower, horizontal member of a conventional garment hanger, the combination having a multitude of uses, especially that of the neat and secure storage of neckties, belts, scarves, stockings, and the like as well as many other types of elongated, flexible, and lightweight articles other than clothing, such as electric and other industrial parts and appliances, of appropriate characteristics and dimensions.

Men's neckties as well as many other such articles of clothing, are readily disarranged and wrinkled in storage, and are also quite readily displaced from a cluttered garment hanger or clothes hook, thereby becoming soiled or damaged. It is both inconvenient and inefficient to look through a whole assortment of such items before the needed article is found. This is time-consuming and unnecessary, according to the unique and basic improvements represented by the instant invention.

Probably the most widely used of these storage devices for clothing is that of the standard garment hanger. Although this provides a ready means for storing elongated items of clothing, merchandise, and the like, it has a distinct disadvantage in that these objects, when loosely suspended from the horizontal member thereof, frequently become intermingled, wrinkled and damaged. Furthermore, there is a very noticeable tendency for these objects to slip from the hanger onto the floor, thus becoming soiled and wrinkled.

Other types of clothing, merchandise and storage racks have been devised for the separation of wearing apparel and the like with varying degrees of efficiency. Some have a large number of parts, thereby necessitating high production costs and commensurately increased sales prices. Others may have a relatively small number of parts but are capable of handling only a very limited and inadequate amount of clothing or other such objects for storage.

The art, therefore, has need of a simple and inexpensive device which can be utilized to store ties, belts, scarves, hosiery, merchandise or industrial and other articles of like character in a neat and orderly fashion, enabling the removal of any one of the stored items with a minimum of time and effort. The device must be suitable for use in all places where the items are likely to be stored. Preferably, the device should also be so designed that it does not need to be installed upon the woodwork, walls, or other foundations in the storage place. Moreover, the device should be mobile so that the objects suspended thereon may be readily viewed for proper selection.

The foregoing problems are resolved and the above specified desirable features supplied by the instant invention which, although originating as a device to deal with clothing storage problems, is also adaptable to a much wider range of uses, as will be readily apparent from the following description thereof.

The primary object of this invention is to provide an

2

efficient storage rack which will maintain in orderly fashion a large number of items in a compact and convenient manner.

Another object of the instant invention is the provision of an inexpensive, yet practical, storage device for neckties, belts, scarves, hosiery and other such elongated articles.

Another object of the instant invention is provision of a divided-type of storage device for industrial equipment or items of merchandise and the like, which will keep them separated in a preselected arrangement and yet will enable the quick and convenient removal of individual units.

Still another object of the instant invention is to provide a storage rack which is easily removable from one location to another and which can be used in all sizes and types of closets or other areas where coat hangers are ordinarily employed.

Another object of the instant invention is the provision of storage racks which do not require mounting thereof on woodwork, walls, etc., but rather may be suspended from any convenient hook, shelf, pipe rack or the like.

Other objects and advantages will become apparent from the following description of a preferred form of the invention, taken in connection with the drawings, in which:

Fig. 1 is a view in perspective of the storage rack suspended from a closet clothes-pole;

Fig. 2 is a plan view of the lower layer of the storage rack divider;

Fig. 3 is a plan view of the upper layer of the storage rack divider;

Fig. 4 is an enlarged view in section taken along the line 4—4 of Fig. 1; and

Fig. 5 is an enlarged view in section taken along the line 5—5 of Fig. 1.

Turning now to the drawings, it will be seen that the invention comprises a lower, arcuate, rectangular-shaped, thin, elongated divider 10 made up of body portion 11, and tabs 12 having edges 13, hinged bottoms 14, and ends 15; an upper stabilizer 20 comprising a body portion 21 of the same size and configuration as the divider 10 but containing, in lieu of tabs 12, transverse slots 22 positioned along said body portion 21, coinciding with the tabs 12 of the divider 10; notches 16 and 23 positioned at both ends of the members 10 and 20, respectively; all suitably positioned on support 30, such as a wire-type coat hanger, for suspending the divider and stabilizer from a place of storage. The tabs 12 are punched upwardly from the divider 10 and are bent into a perpendicular position relative to the longitudinal axis of said divider 10, remaining attached thereto at the hinged bottom 14. The stabilizer 20 fits on top of the divider 10 with the tabs 12 projecting upwardly through their respective slots 22, as best viewed in Figs. 1, 4, and 5. The slots 22 bear against the sides 12a, 12b of the tabs 12 at 17, 18 respectively, and maintain the said tabs 12 in their upstanding position.

In use, the stabilizer 20 is positioned on top of the divider 10 to form the rack 40, whereupon the rack 40 is placed upon a wire-type coat hanger 30, as illustrated in Fig. 3, comprising lateral arms 30a, hook 30b, and bottom cross-member 30c (Figs. 4 and 5). The notches 16 and 23 are arranged so that the corners 30d fit tightly therein and are thereby gripped in such a manner that any tendency for the rack 40 to slip off the coat hanger 30 is averted. The coat hanger 30 then is suspended over a cylindrical or other cross-section rod 32, such as is commonly found in clothes closets. Ties 50, belts 60, scarves 70, and other such items are then placed across the top surface of the rack 40, between the upstanding tabs 12, and efficiently maintained in this position so that

selection of the preferred item is easily accomplished. The material used in construction of the divider 10 and the stabilizer 20 may be any inexpensive yet relatively firm composition, such as heavy paper, cardboard, plastic, or even thin sheetmetal, the nature thereof being determined by cost and ease of handling. The preferred material is cardboard, as it is relatively cheap and can be formed readily into the desired shape.

A feature of the present invention which, although not devoted to the storage of objects in a divided and orderly fashion is, nevertheless, an important attribute thereto, is that—if desired—the tabs 12 may be bent down to lie flat on the member 20, and trousers, skirts or other garments and articles which require proper storage so as not to cause any loss, damage or depreciation in their quality or condition may be placed across the rack 40 and will be thereby protected from creasing or other such damage. The corners 19 and the edges 13 of the tabs 12 act as a stop by engaging the garments or material placed across the rack 40; thus preventing them from displacement and damage.

Although the foregoing description of the invention has been directed primarily to its use as a clothes storage device, it is apparent that many other uses can be made thereof. Practically any type of lightweight, relatively narrow and elongated article may be suspended by this invention, including photographic film, string, wire, articles of merchandise or industry, and many more items which will become apparent to the user.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I. claim:

1. A divided rack for hanging ties, belts, and the like, comprising: a substantially triangular-shaped support having a hook at the top corner for suspending the support from an object and having the side opposite the said hook related to said hook in such a manner that, as the support is hanging freely, the said side is in a horizontal position; and mounted on the top of said side and extending the length thereof a two-layered, arcuate, substantially rectangular and relatively long and thin shaped shelf-like device, the bottom layer containing a plurality of punched-out, upstanding transverse tabs extending upwardly in a position substantially perpendicular to the longitudinal axis of said bottom layer, and the top layer containing a plurality of transverse slots, extending therethrough, positioned to coincide with the said upstanding tabs, said tabs extending through said slots and receiving therefrom support to maintain their upward projection, and a notch at both ends of the two-layered device for encircling the support to prevent the device from disengaging therefrom.

2. The device of claim 1, wherein the tabs of said layered device are shaped as an inverted, truncated pyramid.
